UNITED STATES PATENT OFFICE.

ALBERT BRICKER, OF RANTOUL, KANSAS.

CLAMP.

1,087,719.

Specification of Letters Patent. Patented Feb. 17, 1914.

Application filed April 28, 1913. Serial No. 764,294.

To all whom it may concern:

Be it known that I, ALBERT BRICKER, a citizen of the United States, residing at Rantoul, in the county of Franklin and State 5 of Kansas, have invented certain new and useful Improvements in Clamps; and I do declare the following to be a full, clear, and exact description of the invention, such as will enable others skilled in the art to which 10 it appertains to make and use the same.

This invention relates to improvements in clamps and particularly to clamps for fastening the cable of a drilling machine to its winding drum.

15 A further object is to provide a clamp of this character which will be simple, strong, durable and inexpensive in construction, efficient and reliable in operation and by the use of which one man may readily fasten the 20 cable to and disconnect the same from the drum.

With these and other objects in view, the invention consists of certain novel features of construction, and the combination and arrangement of parts as will be more fully described and claimed.

In the accompanying drawings: Figure 1 is a perspective view of my improved clamp showing the parts in open position ready to 30 receive the cable; Fig. 2 is an end view thereof with the parts closed; Fig. 3 is an enlarged side view partly in section of the clamp with the parts closed or in position for gripping the cable.

35 My improved clamp comprises a base bar or stationary clamping member 1 in the outer edge of which near one end is formed a cable receiving recess 2 and on one end of which are formed parallel apertured lugs 3.

40 Arranged transversely through the bar 1 near the ends thereof are attaching bolts 4 the heads of which are counter-sunk in the outer edge of the bar and which are provided on their outer ends with nuts 5 where- 45 by the clamp may be fastened to the winding drum at any desired position thereon or to the shaft on which the drum is mounted.

50 Adapted to co-act with the base bar or stationary member of the clamp 1 is a movable clamping member 6 comprising a bar having on one end a flattened offset head 7 which is hinged between the apertured lugs 3 of the bar 1 on a pivot pin 8 as shown.

The bar 6 when thus connected to the bar 1 55 is adapted to be swung into engagement with the outer edge of the latter and in the

bar 6 opposite to the recess 2 in the bar 1 is formed a substantially semi-circular recess 10 produced by giving the bar a bend or loop 9. These registering recesses receive the end of the cable when the bar 6 is swung down in operative position on the bar 1 and the clamp thereby securely fastens the same to the winding drum or other object to which the clamp is attached. The 65 free end of the bar 6 is preferably offset on its outer edge to provide a rounded stop lug or projection 11 and secured in the bar 6 near the hinged end thereof is an outwardly extending stud 12 the purpose of which will 70 be hereinafter described.

The hinged clamping member or bar 6 is held in operative engagement with the base bar 1 by a lever 13 comprising a bar having on one end an offset head 14 which is 75 hingedly or loosely connected to the end of the bar 1, opposite from that to which the clamping member 6 is hinged, by a pair of links 15 the opposite ends of which are pivotally connected to the members 1 and 13 80 so that they may pass the opposite sides of the free end of the bar 6 as clearly shown in Figs. 2 and 3 of the drawing. The lever 13 is adapted to be swung down into engagement with the outer side of the clamping 85 member 6 when the latter is in operative position, and in the lever near its free end is formed a bend or loop 16 which overlies and has its inside diameter corresponding with the outside diameter of the loop or 90 bend 9 in the bar 6 with which said loop 16 is engaged when in an operative position. This prevents displacement of the parts longitudinally of each other. Formed in the bar 13 between the bend 16 and the free 95 end of said bar is a transverse passage 17 which, when the bar 13 is in operative position, is adapted to receive the stud 12. This stud holds one end of the lever 13 from slipping laterally off of the member 6, 100 whereas the other end of said lever is held from lateral dislocation by the links 15. In swinging the lever 13 inwardly to an operative position the lug 11 acts as a stop against which the head 14 of the lever 13 105 bears, said lever thus forcing the clamping member 6 into tight engagement with the cable and with the bar 1. After the lever has been swung to a full closed position the lug 11 acts as a stop, which holds the lever 110 against casual opening or releasing movement, but does not prevent the lever from

being manually operated for releasing the cable when desired.

In order to prevent any possibility of the cable slipping when gripped between the 5 clamping members 1 and 6, the inner surfaces of the cable engaging recess 2 and loop 9 of said members are provided with corrugations 18 as shown.

From the foregoing description taken in 10 connection with the accompanying drawings, the construction and operation of the invention will be readily understood without requiring a more extended explanation.

Various changes in the form, proportion, 15 and the minor details of construction may be resorted to without departing from the principle or sacrificing any of the advantages of the invention as claimed.

Having thus described my invention, what 20 I claim is:

The herein described clamp comprising a base bar having a recess in its outer edge, a pair of links pivotally mounted astride

one end of this bar; a clamping bar hinged 25 to the opposite end of the base and having an offset bend in its body producing a recess opposite that in such base, the other end of the clamping bar adapted to be passed between said links and having a lug on its outer edge; a stud projecting from 30 the outer edge of said clamping bar near its hinge, and a lever having a head at one end pivoted between the outer ends of said links and adapted to engage said lug, its body having an offset bend adapted to overlie that 35 in the clamping bar and beyond said bend a passage adapted to receive said stud and prevent lateral displacement of the parts.

In testimony whereof I have hereunto set my hand, in presence of two subscribing witnesses. 40

ALBERT BRICKER.
